EDWARD J. BROOKS,
By his Attorney

UNITED STATES PATENT OFFICE.

EDWARD J. BROOKS, OF EAST ORANGE, NEW JERSEY, ASSIGNOR TO E. J. BROOKS & COMPANY, OF NEW YORK, N. Y.

SEAL.

SPECIFICATION forming part of Letters Patent No. 373,008, dated November 8, 1887.

Application filed September 19, 1887. Serial No. 250,094. (No model.)

To all whom it may concern:

Be it known that I, EDWARD J. BROOKS, a citizen of the United States, and a resident of East Orange, in the State of New Jersey, have 5 invented or discovered a new and useful Improvement in Seals, of which the following is a specification.

This invention relates to those seals which are fastened by compressing and stamping 10 cast-metal seal-disks in or by means of seal-presses.

The present improvement is additional to those of my improvements in such seals patented September 1, 1874, United States Patent No. 154,639; February 26, 1884, No. 294,193, 15 and June 30, 1885, No. 321,275. Its object is to provide more simply and more efficiently against in any way opening the pressed seal-disk or seal proper, so as to release either end 20 of the shackle, and then restoring the appearance of the seal-disk, and thus to insure more absolutely the detection of violations of such seals or of any tampering therewith.

Compressible seal-disks of cast metal have 25 heretofore been commonly made of lead, apart from the distinct hard-metal locking devices or guards inclosed within my improved seals, hereinbefore referred to, and like inclosed locking or anchoring devices, which add materially to the first cost of the seals, and only 30 partially prevent opening such seals by "lifting" and replacing the lead, especially if the seal-disks are not thoroughly solidified in pressing them. This is peculiarly true of "recessed" seals, such as those set forth in my 35 specifications forming part of United States Patents dated February 14, 1882, No. 253,674; March 4, 1884, No. 294,576, and August 9, 1887, No. 368,126; and the press-fastened 40 shackle ends of those recessed seals in which one shackle end is cast fast in the seal-disk, are the most liable to be so tampered with, as the solid portion inclosing the "cast-in" end resists the solidification of the remainder of 45 the seal-disk to a greater or less extent.

I have discovered that an alloy of lead and a hard and brittle metal, as antimony, can be formed of which seal-disks may be cast which 50 are compressible, so as to be solidified in the seal-presses to the requisite extent to preclude withdrawing the press-fastened end or

ends of the shackle, and which at the same time are so brittle that bending and rebending any part of the seal-disk insures a fracture that can be readily detected; and my present 55 invention consists, first, in a seal having a cast-metal seal-disk of such compressible brittle alloy as a new article of manufacture; secondly, in a recessed cast-metal seal-disk of such compressible brittle alloy, in combination with 60 a shackle-wire, and, thirdly, in a recessed cast-metal seal-disk of such compressible brittle alloy, in combination with a shackle-wire upon one end of which the seal-disk is cast fast, as hereinafter more fully set forth. 65

A sheet of drawings accompanies this specification as part thereof.

Figure 1 of these drawings is a perspective view of a recessed seal with cast-in wire fully illustrating this invention. Fig. 2 is a like 70 view of the same applied to a pair of car-door staples and ready for the press. Fig. 3 is a perspective back view of its seal-disk pressed. Fig. 3^x represents a magnified cross-section of the pressed seal. Fig. 4 is a perspective 75 view of a different style of recessed seal-disk cast separate from the wire. Fig. 5 is a like view of the same pressed upon the two ends of a shackle-wire, and Figs. 6 and 7 are perspective views of seals pressed, in other ways 80 illustrating the same invention.

Like letters of reference indicate corresponding parts in the several figures.

In carrying out this invention I melt together lead and antimony in the proportion 85 of about one-seventh antimony to six-sevenths lead, and from these proportions down to one-tenth antimony and nine-tenths lead (more or less) for softer seals. The alloy thus produced is cast into seal-disks of any approved 90 pattern, as A, Fig. 1, or B, Fig. 4, and the seal-disks thus produced are compressible in ordinary seal-presses either between dies of any approved face conformation, as illustrated by Figs. 3, 3^x, 5, and 6, respectively, or in 95 my roller seal-presses, as represented by Fig. 7.

At the same time the alloy is so brittle that, after the seal-disk is pressed, it is practically impossible to bend the seal-disk or to raise any part of the metal, and then restore 100 it to its original shape without breaking the seal-disk or the portion tampered with in the

act of rebending it. Consequently after the seal-disk is solidified, or even closed around the ends of a suitable shackle-wire, as W or W^2 or W^3 or W^4 , so as to be stamped with the 5 requisite distinguishing-marks m , it is practically impossible to take out either shackle end by cutting and bending the seal-disk, or by reopening its threading-holes h or recess r without sure detection.

- 10 The harder the alloy is, provided it will press and take the impression of the dies or rollers, the safer is the seal. I consequently prefer to use about one-seventh of antimony to six-sevenths of lead; but well-pressed seal-disks, containing as little as one-tenth antimony to nine-tenths lead, as aforesaid, are considered reasonably secure against being successfully tampered with in the manner indicated.
- 20 The seal represented by Figs. 1, 2, 3, and 3^x is constructed, apart from the present invention, substantially in accordance with Fig. 6 of said Patent No. 368,126, of August 9, 1887, its seal-disk A being cast fast on one end, a , 25 of a shackle-wire, W , and having a pair of threading-holes, h , in its top, and a horse-shoe-shaped recess, r , in its face, which receive the other shackle end, b , as illustrated by Fig. 2, after passing the wire through a 30 pair of car-door staples, S , or the like, after which the seal is compressed and stamped in any approved way, as illustrated by Figs. 3, 3^x , to fasten the threaded shackle end b , and to provide the closed seal-disk with its distinguishing-marks m . In using very thin single wire, as represented by W , the threaded end b is preferably drawn back across the seal-disk, so as to be embedded in the same at the pressing operation, as represented at c in Figs. 35 and 3^x , and the brittle metal precludes removing and replacing this rebent outer portion of the wire without so marring the seal-disk that the act can be detected.

The seal represented by Figs. 4 and 5 is constructed, apart from the present invention, in 45 accordance substantially with Figs. 7 and 8 of said Patent No. 368,126, of August 9, 1887, having a separately-cast seal-disk, B , provided in the molds with threading-holes h in its top, 50 and a horse-shoe-shaped recess, r , in its face and lower edge, which receive both ends of a shackle, W^2 , of ordinary commercial wire, after which it is compressed and stamped, as illustrated by Fig. 5.

The seal represented by Fig. 6 has a cast-metal seal-disk, C , of my compressible brittle alloy, with parallel threading-holes h closed upon the ends of a shackle-wire, W^3 , provided with my detector-indentations i , patented June 27, 1876; and the seal represented by Fig. 7 has 60 a similar seal-disk, D , compressed upon the ends of a shackle-wire, W^4 , provided with my detector-enlargements e , patented July 3, 1877.

The seals above described are shown by way of illustration. It will be understood that my 65 compressible brittle alloy may be used for seal-disks or seals proper of any approved pattern, and that these may be combined with shackles of any suitable kind. Other substances may also be combined with lead in making said 70 alloy, so long as the characteristics hereinbefore set forth are preserved.

I do not claim herein seals having non-compressible seal-disks of hard and brittle metal. Such seals are set forth in my specifications 75 forming part of United States Patents, dated May 6, 1884, No. 298,168; March 17, 1885, No. 314,164; June 23, 1885, No. 320,904, and September 7, 1886, No. 348,884, and form no part of my present invention. Neither do I limit 80 myself to the exact proportions hereinbefore set forth, as lead itself varies somewhat as to softness, and more or less of the hard and brittle metal will be required with softer or harder lead to render the alloy at once compressible 85 and sufficiently brittle to prevent bending up and replacing any part of the seal-disk.

Having thus described my said improvement in seals, I claim as my invention and desire to patent under this specification— 90

1. A seal having a cast-metal seal-disk composed of a compressible brittle alloy, substantially as herein specified, as a new article of manufacture.

2. In combination with a suitable shackle-wire, a recessed cast-metal seal-disk composed of a compressible brittle alloy, substantially as herein specified, whereby reclosing its recess after tampering with the seal-disk is prevented. 95

3. In combination with a suitable shackle-wire, a recessed seal-disk cast fast on one end of the wire and composed of a compressible brittle alloy, substantially as herein specified, for the purposes set forth. 100

EDWARD J. BROOKS.
